UNITED STATES PATENT OFFICE.

JOHN J. PLEGER, OF CHICAGO, ILLINOIS.

COVERING MACHINE.

Application filed April 6, 1927. Serial No. 181,458.

This invention relates to improvements in machines for attaching covers to books, and more particularly to that type of machine adapted to attach paper covers to pamphlets 5 and the like.

One of the principal objects of the invention is to provide novel and improved means for applying adhesive to the cover, and the invention further resides in a generally improved construction involving novel details and features hereinafter set forth and illustrated in the attached drawings, in which:

Figure 1 is a side elevation of one end of a machine made in accordance with my invention;

Fig. 2 is a side elevation of the other end of the machine, Figs. 1 and 2 forming together a complete side elevation;

Figs. 3 and 4 are plan views corresponding to the parts of the machine shown respectively in Figs. 1 and 2;

Fig. 5 is an enlarged plan view of a fragment of that end of the machine shown in Fig. 3;

Fig. 6 is a section on the line 6—6, Fig. 5;

Fig. 7 is a transverse section on the line 7—7, Fig. 6;

Fig. 8 is a fragmentary sectional view on the line 8—8, Fig. 4;

Fig. 9 is a view in perspective of one of the conveyer lugs;

Fig. 10 is an elevation of the forward end of the machine showing the opposite side to that shown in Fig. 2;

Fig. 11 is an elevation of the transverse conveyer at the delivery end of the machine;

Fig. 12 is a plan view of the forward end of the conveyer shown in Fig. 11;

Fig. 13 is a section on the line 13—13, Fig. 40 and 11;

Figs. 14 to 21, inclusive, are diagrammatic views illustrating the various operations of the machine in the complete process.

Referring to the drawings, the machine comprises framework including legs or pedestals 1 and parallel spaced side beams 2 supported on said pedestals. At one end of the frame, as shown in Fig. 1, is mounted transversely of the machine a feed table or chute 3, this being pivotally mounted at 4 to permit angular adjustment. Adjacent the inner end of the table 3 are a pair of transverse shafts 5 and 6 which carry contacting feed rolls, 7 and 8 respectively, adapted to pass

the cover sheets received from the table 3 onto 55 supporting guide bars 9 which extend longitudinally of the frame and are supported on transverse cross bars 11, see Fig. 3. The rolls 7 and 8 may be advantageously provided with soft or sponge rubber faces. 60

It will be noted that the table 3 is provided with transversely adjustable flange pieces 12 which may be adjusted in accordance with the width of the sheets to be fed into the machine and which function to accurately guide 65 the sheets to the feed rolls 7 and 8. It will also be noted that the shafts 5 and 6 are provided with a plurality of rolls 13, the rolls of one shaft engaging the rolls of the other shaft in pairs to act as supporting rolls for 70 the sheets as they pass between the feed rolls 5 and 6. In order to control the pressure between the feed rolls, the bearings of the shaft 5 are made vertically adjustable, and adjustment thereof may be made manually through 75 the medium of a shaft 14 which is operatively connected with the said adjustable bearings through the medium of vertical screw shafts 15, see Fig. 1, and bevel gears 16. The shaft 14 has at one end an operating wheel 17 by 80 means of which the shaft may be rotated. Any mechanical paper feeder suitable for this purpose can be attached; or covers can be fed manually.

In order to advance the sheets along the 85 supporting bars 9 and through the various mechanisms which operate upon said sheets as hereinafter described, I provide a pair of endless conveyer chains 18 which operate upon sprockets 19 on the shaft 6 and on 90 sprockets 21, 21 on a transverse shaft 22 suitably journaled in the side bars 2 of the frame. Intermediate the shafts are tensioning sprockets 23 which as shown in Fig. 1 are mounted on a transverse bar 24 secured to 95 two of the uprights 1. The upper runs of the chains 18 move as shown in Fig. 7 in a plane slightly below the upper edges of the bars 9, but the chains carry at spaced intervals lugs 25 which on the upper run of the 100 chain project upwardly beyond the tops of the said bars 9 and engage the sheets resting on the said bars to advance them along the latter, it being understood that during operation of the machine the chains are in continuous operation. 105

Adjacent the bars 9 at one side is a recessed guide bar 26 which is adapted to receive one

edge of sheets supported by the bars 9, and on the opposite side of the bars 9 from the guide bar 26 are a plurality of flexible elements 27, see Fig. 3, which project into the path of the sheet and hold the latter against and in the guide bar 26, the spring elements 27 being of such resilient strength as to insure the proper positioning of the sheet against the guide bar without tendency to crumple or distort the sheet from its normal flat condition. In the present instance, the elements 27 are supported on a bar 28, which in turn is carried by the transverse bars 11.

It will be noted from the foregoing description that sheets passed onto the bars 9 as described are carried along the latter by the moving chains 18. In this movement, the sheets eventually pass between positioning rolls 29, 29 mounted on transverse shafts 31 and 32, as shown in Fig. 6. The shaft 31 is carried by a pair of bell crank levers 33 pivotally secured to the frame pieces 2, as shown in Fig. 3. These bell crank levers are adjustably controlled by means of studs 34 which project from the sides of a fixed beam 35 on the frame and through the upper projecting arms of the bell crank levers 33, as shown in Fig. 6. A nut 36 on each of the studs 34 and a spring 37 confined between the lever 33 and the beam 35 afford means for adjusting the bell crank levers angularly about their pivots 38 to thereby adjust the shaft 31 and the rolls 29 thereon vertically and with respect to the rolls 29 on the shaft 32, the latter being relatively fixed.

Immediately in back of the rolls 29 are two sets of scoring rolls 39, these rolls operating in vertically arranged pairs. The upper ones of the rolls 39 are carried by brackets 41 adjustable transversely on the bar 35, as best shown in Fig. 6, and held in adjusted position on the said bar by means of set screws 42. The lower of the scoring rolls are carried upon a transverse shaft 43 mounted in the side beams 2, and this shaft 43 also carries outwardly of the scoring rollers and one on each side thereof a pair of rubber-faced positioning rolls 44 which coact with similar rolls 45 supported in brackets 46 slidably supported on the beam 35 and held in adjusted position on said beam by set screws 47. The rollers 29 and the rollers 44 and 45 are adapted to hold the sheets in position while the scoring rolls 39 are operating thereon. It will be noted that the upper scoring rolls 39 and the upper positioning rolls 45 are adjusted vertically in the brackets which carry them by means of adjusting nuts 48 at the tops of the brackets, as shown in Fig. 6.

One of each cooperating pair of scoring rollers has a peripheral and circumferential groove while the periphery of the companion roller is formed to fit into the said groove. By reversing the relative positions of these rollers the sheets may be grooved from either

side as desired. In the present instance, the sheets are given four scorings, the two central scorings which, as shown in Figs. 15 to 18, register with the rear edges of the book and which accordingly are spaced in accordance with the thickness of the latter, being made from the upper or inner surface of the cover sheet, and the two outer scorings which, as shown in Fig. 21, form the hinges on which the cover bends away from the book, are made from the under side of the sheet which constitutes the outer surface of the cover.

From the scoring rolls the sheets, traveling with the chains 18 as previously set forth, pass under a gluing roll 51, this roll being carried by a transverse shaft 52 mounted in the side frames and having surface contact with a flanged roller 53 mounted above the roll 51 on a transverse shaft 54, and this roller 53 in turn has surface contact with a third roller 55 on a shaft 56 journaled in bearings on a receptacle 57 mounted in the frame. The roller 55, as shown in Fig. 6, extends into the receptacle, which in operation contains an adhesive which is fed from the face of the roller 55 to the roller 53, and thence to the roller 51. As shown in Fig. 7, the roller 51 is so mounted that at the bottom it lies slightly above the plane of the top of the sheet-supporting bars 9 so that in the absence of means for elevating the sheets, as hereinafter described, the sheet will pass under without coming in contact with the said roll 51.

Means is provided, however, for elevating the sheets as they pass under the roller 51 so that suitable amounts of adhesive are transferred from the roll to the sheet. This mechanism is best illustrated in Figs. 6 and 7, and consists of an arm 58 which is secured to and extends rearwardly from the under side of the receptacle 57 or, as in the present instance, from the bottom of a heating element 59 located beneath the receptacle 57. This arm 58 extends to a position opposite the roller 51, and its forward end is slightly upturned so that a sheet advanced by the chains as described will pass under the said arm 58. The outer end of the arm is slotted for reception of a pair of forked levers 60 and 61, the lever 60 being positioned slightly in advance of the lever 61, as shown in Fig. 6. The lever 60 is attached at its lower end to a block 62 which is journaled between members 63 and 64, as shown in Fig. 7, so as to be readily movable about its axis, and the block 62 also has projecting forwardly therefrom an arm 65 which immediately overlies one end of a lever 66 pivotally mounted at 67 in the frame and extending transversely of the machine. The opposite end of the lever 66 underlies one end of a lever arm 68 which is pivotally secured at 69 to the upper end of an arm 70 which is secured to a rock shaft 72 journaled in the frame between points 73, 73, as shown in Fig. 7. This shaft 72 also carries

the lever 61, and the shaft is counterbalanced against the weight of the parts referred to by means of a counterbalance weight 74, see Fig. 6, which is adjustable longitudinally of an arm 75 projecting from the shaft. The lever 68 has in its upper side a notch 75 which, when the said lever is elevated, is adapted to receive the lower end 76 of a depending arm on a transverse rock shaft 77, which shaft is journaled between points 78, 78 on the frame. This shaft carries near its center arms 79 between which is journaled a roller 81 which occupies a position directly below the roller 51, as well shown in Fig. 7. The weight of the parts carried by the shaft 77 is accurately counterbalanced by a weight 82 on an arm 83 which projects from the said shaft.

It will now be seen that a sheet advanced by the chains 18 as previously described will, after passing between the scoring rolls, engage the lever 59 and will depress this lever. As a result, the arm 65 is also depressed and will carry with it one end of the lever 66, with the result that the lever 68 is elevated around the pivot 69, thereby engaging the depending arm 76 in the notch or recess 75 in the said lever 66. Immediately after engaging and depressing the lever 59, the sheet engages the lever 61 and depresses this lever, with the result that the shaft 72 is rocked and the arm 68 is advanced in the direction of movement of the sheet carrying with it the arm 76 of the shaft 77. The rocking in this manner of the shaft 77 results in an elevation of the arm 79 and the roller 81 which presses the sheet which is then between the rollers 51 and 81 against the former, with the result that glue is transferred to the sheet. As soon as the rear end of the sheet leaves the lever 59, the roller 81 is released and moves downwardly. By properly placing the levers 59 and 61 with respect to roller 51 and to each other the adhesive transferred to sheet may be confined to an area whose borders lie well within the edges of the sheet.

Positioned at the rear of the adhesive container 57 and supported at that end by a transverse cross bar 85, see Fig. 3, is a table 86 which is elevated slightly above the bars 9 on which the sheets travel, as previously described. The top of the table 86, however, is lower than the tops of the carrying lugs 25 on the chains 18, and the table is divided longitudinally to provide for passage of the lugs of the chains. At both longitudinal edges, the table is flanged vertically, as indicated at 87 and 88. This table is adapted to receive the books or pamphlets which are to be bound by the sheets normally fed to the machine, as described, from the table 3. The books are placed on the table so that the bound or closed edge lies against the flange 87, which as shown is located approximately at the longitudinal center line of the machine, and the lugs 25 on the chain engaging the book ad-

vance it along the table 86 and directly above the sheet which, as previously described, has received an application of adhesive and is traveling with the chain on the supports 9 below the table 86. The relative positions of the sheet and book may be varied by means of set screws 25^a in the tops of the lugs 25 which are placed so that the heads thereof engage the books. Resilient fingers 89 similar to the fingers 27 which retain the sheet against the bar 26 as previously described are adjustably mounted above the table 86, as shown in Fig. 4, to retain the edge of the book against the flange 87. At this point, also, in the machine a second set of the sheet-controlling fingers 27 is provided to insure proper positioning of the sheet as it advances beneath the table 86.

The rear ends of the chains 18 and the shaft 22 lie under the end of the table 86, as clearly shown in Fig. 4. Immediately adjacent the end of the said table is a conveyer consisting of a pair of opposed endless belts 91 and 92 which operate on pulleys 93 and 94 suitably mounted in the main frame, the belt 91 being positioned above the belt 92, as clearly shown in Fig. 2, and the two operating together to continue the movement of the pamphlet and the covering sheet which are fed between them by the chains 18. A set of spring-pressed rollers 95 mounted immediately above the lower run of the conveyer 91 controls the upward movement of the latter and insures a proper frictional grip upon the book passing underneath the conveyer, while a corresponding set of rollers 96 is located immediately below and supports the upper run of the conveyer 92. Each of the belts is provided with an adjustable idler puller 97 by means of which the tension of the belts is controlled. These idlers in the present instance are journaled on the ends of pivoted arm 98 having notched edges engaged by a detent 99 which acts to hold the arm in the extended belt-tensioning position, as clearly illustrated in Fig. 2. The belts function not only to continue the forward movement of the book and cover sheet, but also grip or clamp these two elements together in proper relative position, and means is provided for vertically adjusting the belt 91 with respect to the belt 92 to accommodate different thicknesses of books. The entire upper belt structure is vertically adjustable through screws 150 which are rotatably mounted in frame brackets 151, and the screws may be simultaneously turned through a hand wheel 152 on a shaft 153 operatively connected through spiral gears 154 and 155 with the said screws.

As shown in Fig. 4, the belts 91 and 92 are relatively narrow and are positioned with respect to the flange 87 so that the back of the book projects appreciably beyond the edges of the belts, as also does the binding sheet which occupies a position beneath the book,

as shown in Fig. 16. As the sheet and book now occupying a predetermined relative position pass between the conveyers 91 and 92, the forward edge of the sheet engages an upwardly and inwardly inclining rod 101, see Fig. 4, which functions to elevate that side of the sheet to a vertical position as shown in Fig. 18. At the same time, a set of rollers 102 engage the under side of the sheet at the rear edge of the book and press this portion of the sheet which has received the adhesive against the book. The continued advance of book and sheet results in a complete elevation of that portion of the sheet extending beyond the rear edge of the book until the sheet passes into a longitudinal guide slot 100. In advance of the passage of the sheet into the guide and slot a roller 103 comes into action, see Fig. 18, to press the sheet against the back of the book. While moving in the slot 100, a vertical 104 and a series of coacting horizontal and vertical rollers 105 and 106, see Figs. 19 and 20, function to press the center portion of the cover containing the adhesive firmly around the back of the book. The action of the rollers is aided by the scored lines which correspond accurately with the rear edges of the book around which the sheet is bent, as previously set forth. As a result, the book and cover when they leave the conveyers 91 and 92 are properly joined together.

Attention is directed to the roller 104, see Fig. 19, which is adjustable to accommodate different thicknesses of books and which is adapted to roll the cover sheet around and against the back and sides of the book.

On leaving the conveyers 91 and 92, the books pass onto a table 107 and are fed transversely along the table by means of oscillating bars 108 which receive their motion from a crank 109 driven from the shaft 139 through transmission gearing.

As shown in Figs. 11, 12 and 13, the table 107 consists of a pair of spaced parallel bars 156 between and on the outsides of which the bars 108 oscillate. The forward ends of the bars 108 rest on rollers 157 and with the crank 109 rotating in the direction indicated the intermittent feeding action of the conveyer will be apparent. The throw of the crank 109 is adjustable to control the conveying action.

The various parts of the aforescribed mechanism receive their movements from an electric motor 121 mounted in the frame, as shown in Fig. 1. This motor is connected through suitable transmission including gears 122 and 123 with a shaft 124 extending longitudinally of the machine. The shaft 124 is connected through a chain 125 with a shaft 126 also extending longitudinally of the frame, and the forward end of this shaft is connected through bevel gears 127 and 128 and a gear 129 with a gear 131 journaled in the frame, and this gear carries a crank 132 to which is pivotally secured a rack 133. This

rack engages a pinion on the shaft 5, which pinion is connected with the shaft through a suitable pawl and ratchet, as indicated at 134 in Figs. 1 and 3. By means of this gearing, the shaft 5 is given an intermittent rotary movement which periodically and at proper intervals feeds sheets from the table 3 onto the bars 9, as previously set forth. The shaft 126 is also operatively connected through suitable gearing including a bevel pinion 135 with the shafts 32 and 43 which respectively carry the rollers 29 and the lower scoring rolls 39 whereby these rolls are continuously rotated. The shaft 126 is also operatively connected through bevel gears 136 and 137 with the shaft 22 and therethrough with the sprockets which operate the chains 18. At the rear end of the machine the shaft 126 is connected through a clutch 138 with an aligned shaft 139 which through bevel gears 141 and 142 is connected with a transverse shaft 143 which carries the roller upon which the rear end of the belt 92 travels. The shaft 139 also is connected through suitable gearing with a stub shaft 144 which through bevel gears is connected with a transverse shaft 145 which carries the roller 94 on which the rear end of the belt 91 operates. The clutch 138 is controlled manually through a hand lever 146 which is connected with the clutch to suitable linkage including an arm 147, connecting rod 148 and lever 149.

At its front end the shaft 124 is connected through a vertical shaft 151 with the shafts 56, 54 and 52 which carry the gluing rolls 55 whereby these rolls are given a positive and continuous rotation. It will be noted further that the machine is adjustable for reception of binding sheets of different widths, the guide bar 26, the bar 28, the rolls 29 and the scoring rolls 39 being all transversely adjustable with respect to each other.

I claim:

1. In a binding machine, the combination with cover-sheet conveying means, of a plurality of pairs of cooperating scoring rolls adapted to operate on the sheets advanced by said conveyer, one roll of each pair being grooved for the reception of the scoring periphery of the companion roll, and the said pairs of rolls being separated by a space corresponding substantially with the thickness of the book to which the sheet is to be applied. 110

2. In a binding machine, the combination with a plurality of pairs of scoring rolls, one roll of each pair being circumferentially grooved at the periphery and constituting the female member of the scoring device of which the companion roll is the male member, and means for passing cover sheets through the rolls, said rolls being spaced apart in accordance with the thickness of the books to which the covers are to be applied. 125

3. In a binding machine, the combination with two rotary shafts, of a plurality of scor- 130

- ing rolls mounted on the shafts, with the rolls of one shaft adapted to cooperate individually with the rolls on the other shaft to constitute a plurality of independent scoring devices, means for passing a cover sheet between said rolls, and means whereby certain of said cooperating pairs of rolls score the sheet from one side while others score the sheet from the opposite side.
10. In a binding machine, the combination with a plurality of pairs of cooperating scoring rolls, one roll of each pair being grooved circumferentially at the periphery and constituting the female member cooperative with the ungrooved periphery of the companion roll, and means for passing a sheet between said rolls whereby the latter is scored from opposite sides simultaneously in accordance with the width of the book to which the cover is to be applied.
15. In a binding machine, the combination with scoring means consisting of at least one pair of cooperating scoring rolls, one of the said rolls being grooved circumferentially at the periphery and the other of said rolls operating in said groove, and means for adjusting the relative positions of the rolls to vary the extent to which the periphery of one roll enters the peripheral groove of the companion roll.
20. In a binding machine, the combination with means for supporting a cover sheet and a book in superimposed and spaced relation, of receiving means adjacent the supporting means, and means including a moving element engaging both the sheet and book for transferring them to the receiving means in superimposed contacting relation.
25. In a binding machine, the combination with means for supporting a cover sheet and a book in superimposed and spaced relation, of receiving means adjacent the supporting means, means including a moving element engaging both the sheet and book for transferring them to the receiving means in superimposed contacting relation, and adjustable means in said element for determining the relative positions of the superimposed sheet and book.
30. In a binding machine, the combination with means for supporting a cover sheet and a book in superimposed and spaced relation, of receiving means adjacent the supporting means, means including a moving element engaging both the sheet and book for transferring them to the receiving means in superimposed contacting relation, and adjustable means in said element adapted to engage the book for determining the relative position of the superimposed sheet and book.
35. In a binding machine, the combination with a conveyer comprising means for retaining a cover sheet and a book in proper relative positions, with one side of the book lying against the corresponding side of the cover sheet and with the opposite side of the cover sheet extended, of means located adjacent the conveyer for folding the extended portion of the sheet around the back and the uncovered side of said book.
40. In a book binding machine, the combination with a conveyer, of means for passing a cover sheet and a book to said conveyer, with one side of the book lying against a corresponding side of the cover sheet and with the other side of the cover sheet extended, and means adjacent the conveyer for folding the extended portion of the sheet around the back and the uncovered side of said book.
45. In a book binding machine, the combination with a conveyer for a cover sheet, of means for scoring the sheet from one side along parallel lines spaced in accordance with the thickness of the book to which the cover is to be applied, and means for scoring the sheet from the opposite side along parallel lines running adjacent to and outwardly of the scored lines first mentioned.
50. In a book binding machine, the combination with a conveyer for a cover sheet, of means for scoring the sheet from one side along parallel lines spaced in accordance with the thickness of the book to which the cover is to be applied, means for scoring the sheet from the opposite side along parallel lines running adjacent to and outwardly of the scored lines first mentioned, means for relatively positioning the book and the cover sheet so that one rear edge of the book corresponds with one of the inner scored lines, a conveyer adapted to receive the book and cover in the aforesaid relative positions from the positioning means, and means adjacent the conveyer adapted to fold the extended portion of the cover sheet around the back of the book to bring the other of the inner pair of scored lines into a position registering with the other back edge of the book, substantially as described.
55. In a binding machine, the combination with a conveyer, of means for feeding a cover sheet and a book to said conveyer in horizontal superimposed position, and means adjacent the conveyer for folding the cover around the book as it is advanced on the conveyer.
60. In a binding machine, the combination with opposed endless conveyers, of means for passing a book and a cover sheet therefor between the conveyers in predetermined relative position and with one side of the cover sheet extended, resilient means operatively associated with the conveyers for securely holding the book and cover sheet in the aforesaid relative position, and means located adjacent the conveyers and acting upon the cover sheet as it advances in the conveyer to fold the extended portion of said sheet around the back of said book.
65. In a book binding machine, the combination with a pair of opposed endless con-

veyers, of a plurality of relatively fixed rolls positioned in back of the inner run of one of the conveyers, a second set of rolls correspondingly positioned with respect to the other conveyer, and resilient means tending to hold the rolls of said second set in an advanced position determining the space between the adjacent runs of the two conveyers.

16. In a book binding machine, the combination with a conveyer including means for retaining a cover sheet and the book in horizontal superimposed relation with the book overlying one side of the cover sheet and the other side of the cover sheet extended beyond the back of the book, means for elevating the extended part of the sheet, means for folding the mid portion of the sheet closely around the back and the adjacent portions of the sides of the book, and means including rollers engaging the back and the top and bottom sides of said book adjacent the back for forcing the sheet firmly against the book.

17. In a book binding machine, the combination with a conveyer including means for holding a book and a cover sheet in superimposed horizontal position with the book overlying one side of the sheet and the opposite side of the sheet being extended beyond the back of the book, of means adjacent the conveyer for elevating the sheet, a roller for bringing the sheet into close contact with the back of the book, a second roller adapted to press the sheet against the back and the adjacent portions of both the upper and lower sides of the book, and means including rollers engaging both the upper and lower sides and back of the book for wiping the cover closely against the book surfaces.

18. In a binding machine, the combination with opposed endless conveyers, of means for feeding a book and a cover sheet therefor between said conveyers with one side of the book against one side of the sheet and with the other side of the sheet extended, means adjacent the conveyers for folding the extended portion of the sheet around the back of the book, means for regulating the tension of the respective conveyers including in each instance a pivotally notched arm having an idler roller at the outer end engaging the conveyer, and a pawl operating in conjunction with said notched edge to retain the pivoted

arm in extended and conveyor-tightening position.

19. In a book binding machine, the combination with superimposed supports upon which respectively a book and cover sheet are adapted to lie flat, of means for predeterminedly and relatively positioning said book and cover upon the supports, receiving means for said book and cover, means for sliding the book and cover from their respective supports so that they lie upon said receiving means in predetermined relative positions with one side face of the book against one side of the cover sheet and with a predetermined portion of the sheet extending beyond the rear edge of the book, and means for folding said extended part of the sheet around the rear edge and against the other face of the book.

20. In a book binding machine, the combination with means for applying a strip of adhesive to a cover sheet in predetermined position, of mechanism for bringing a book and cover sheet together with one side face of the book in contact with the cover sheet at one side of the adhesive strip and with a rear corner of the book in predetermined parallel relation to said strip, and means for folding the sheet around the rear edge and other side of the book with the adhesive in contact with said rear edge.

21. In a book binding machine, the combination with means for scoring a cover sheet on parallel spaced lines, of means for applying an adhesive to the sheet between said lines, mechanism for bringing a book and cover sheet together with one side face of the book in contact with the cover sheet at one side of the adhesive strip and with one rear corner of the book on one of the scored lines, and means for folding the sheet around the rear edge and other side of the book with the adhesive in contact with said rear edge.

22. In a binding machine, a cover-applying roll comprising a cylindrical portion adapted for engaging the rear edge surface of a book, said cylindrical portion terminating at each end in an extended circumferential convexed flange, which flanges are adapted to engage the opposite side surfaces of the book adjacent the rear edge to press a cover tightly around and against said surfaces.
